CLAIM

The ornamental design for a box rope as shown and described.

DESCRIPTION

FIG. 1 is a side perspective view of a box rope showing my new design;

FIG. 2 is a front view with the rear view being a mirror image thereof;

FIG. 3 is a top view thereof; and,

FIG. 4 is a bottom view thereof.

The broken lines represent portions of the box rope which form no part of the claimed design. The broken lines represent break lines and form no part of the claimed design.

1 Claim, 4 Drawing Sheets
